US00D615585S

(12) **United States Design Patent**
Skinner et al.

(10) **Patent No.:** US D615,585 S
(45) **Date of Patent:** ** May 11, 2010

(54) **TRANSACTION CARD**

(75) Inventors: **Rebecca Skinner**, Minneapolis, MN (US); **Daniel P. Guidera**, Northampton, MA (US)

(73) Assignee: **Target Brands, Inc.**, Minneapolis, MN (US)

(**) Term: **14 Years**

(21) Appl. No.: **29/346,476**

(22) Filed: **Oct. 31, 2009**

(51) **LOC (9) Cl.** 19-08

(52) **U.S. Cl.** D19/10

(58) **Field of Classification Search** D19/1-34; 40/124.01-124.15, 672, 661, 726, 776, 617; 283/72, 74, 75, 103, 105, 106; 235/380; 206/449; D21/385; D20/10, 22, 27, 40, D20/42, 11; D14/435-437; D25/141, 149, D25/156

See application file for complete search history.

CLAIM

The ornamental design for a transaction card, as shown and described.

DESCRIPTION

FIG. 1 is a front, perspective view of a transaction card showing an embodiment of our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The features shown in broken lines depict environmental or other associated subject matter and form no part of the claimed design.
